US00D966104S

(12) **United States Design Patent** (10) **Patent No.:** **US D966,104 S**
Yuan (45) **Date of Patent:** **** Oct. 11, 2022**

(54) **CONTAINER**(71) Applicant: **Conopco, Inc.**, Englewood Cliffs, NJ (US)(72) Inventor: **Huijie Yuan**, Shanghai (CN)(73) Assignee: **Conopco, Inc.**, Englewood Cliffs, NJ (US)(***) Term: **15 Years**(21) Appl. No.: **29/720,225**(22) Filed: **Jan. 10, 2020**(30) **Foreign Application Priority Data**

Jul. 19, 2019 (EM) 006636601-0001

(51) **LOC (13) Cl.** ..... **09-01**(52) **U.S. Cl.**USPC ..... **D9/504**; D9/529; D28/76(58) **Field of Classification Search**

OTHER PUBLICATIONS

Co-pending application entitled, "Container".

Primary Examiner — Brett Miller

Assistant Examiner — Rani J Abdallah

(74) Attorney, Agent, or Firm — Gerard J. McGowan, Jr.

(57) **CLAIM**

The ornamental design for the container, as shown and described.

DESCRIPTION

The patent or application file contains at least one drawing executed in color. Copies of this patent or patent application with color drawing(s) will be provided by the Office upon request and payment of the necessary fee.

FIG. 1 is a perspective view of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 3 Drawing Sheets

(3 of 3 Drawing Sheet(s) Filed in Color)
